(57) **CLAIM**

The ornamental design for a stanchion assembly, as shown and described.

DESCRIPTION

FIG. 1 is a perspective view of a stanchion assembly of the present invention;

FIG. 2 is a front elevational view of the stanchion assembly of FIG. 1;

FIG. 3 is a rear elevational view of the stanchion assembly of FIG. 1;

FIG. 4 is a left side elevational view of the stanchion assembly of FIG. 1;

FIG. 5 is a right side elevational view of the stanchion assembly of FIG. 1;

FIG. 6 is a top elevational view of the stanchion assembly of FIG. 1; and,

FIG. 7 is a bottom elevational view of the stanchion assembly of FIG. 1.

The broken line showing of structure is for illustrative purposes only and forms no part of the claimed design.
